[57] CLAIM

The ornamental design for a glue dispenser, as shown and described.

DESCRIPTION

FIG. 1 is a side elevational view of a glue dispenser showing my new design, the side opposite being a mirror image thereof;

FIG. 2 is a front elevational view, the rear view being a mirror image thereof;

FIG. 3 is a top plan view;

FIG. 4 is a bottom plan view; and,

FIG. 5 is a cross-sectional view taken in the direction of arrows 5—5 in FIG. 1.

FIG. 1

FIG. 2

FIG. 3

FIG. 4

FIG. 5
